UNITED STATES PATENT OFFICE.

HARVEY C. STROUT, OF PEABODY, MASSACHUSETTS.

BARREL-CLOSURE.

SPECIFICATION forming part of Letters Patent No. 436,161, dated September 9, 1890.

Application filed May 15, 1890. Serial No. 351,863. (No model.)

To all whom it may concern:

Be it known that I, HARVEY C. STROUT, of Peabody, in the county of Essex and State of Massachusetts, have invented a new and useful Improvement in Barrels, of which the following, taken in connection with the accompanying drawings, is a specification.

My invention relates to barrels for use in the transportation of swill and other odoriferous substances; and it consists in certain novel features of construction, arrangement, and combination of parts, which will be readily understood by reference to the description of the drawings, and to the claims hereinafter given, and in which my invention is clearly pointed out.

Figure 1 of the drawings is a plan of a barrel embodying my invention. Fig. 2 is a vertical section of a portion of the barrel, on line *xx* on Fig. 1, and Fig. 3 is an elevation of the locking-cam.

In the drawings, *a a* represent the staves of the body of the barrel; *b*, the wooden head or cover having secured thereto the metal flange-ring *c*, cast in one piece with the spokes *d d* and the central hub *e*, in which is set the stud *f*, as shown in Fig. 2.

The wooden head *b* is made of a diameter slightly less than the inner diameter of the barrel at the chine or end of the staves, and is secured to the flange-ring *c* by means of a series of bolts *g*, and has secured between it and said flange-ring *c* the annular rubber gasket *h*, arranged to rest upon the ends of the staves, the outer diameter of said gasket and also of the flange-ring being equal to the outer diameter of barrel at the ends of the staves, as shown in Fig. 2.

A plurality of ears *i i* are firmly secured to the upper portion of the body of the barrel by suitable bolts *i'*, and each of said stands has pivoted thereto a cam-lever *j*, the outer end of which is made eccentric to its pivotal connection to said stand, so that when its free end is depressed into the position shown in Fig. 2, its opposite end near its fulcrum will bear hard upon the flange-ring *c* and compress the rubber gasket between it and the ends of the staves, so as to form a liquid-tight joint between the head or cover and the end of the body of the barrel.

The outer portion of the hub *e* has formed therein a plurality of rectangular notches or recesses adapted to receive the inner ends of the levers *j*, as shown in dotted lines in Fig. 1. 55

The stud *f* has mounted thereon, so as to be freely movable about the axis thereof, the locking-hub *k*, provided with the rectangular slots *k'*, for the passage of the inner ends of the levers *j*, and with the holes or sockets *l*, 60 for the reception of a spanner as a means of rotating said hub for the purpose of locking said levers *j j* in the position shown in the drawings.

The under sides of the portions of the hub *k* which project therefrom between the slots *k'* are slightly inclined, so as to form cam-surfaces, as shown at *m* in Fig. 3, which serve to clamp the ends of the levers *j j* firmly between it at the bottoms of the notches in the hub *e*, 70 as shown in Fig. 2.

By moving the hub *k* about its axis until the slots *k'* therein are directly over the ends of the levers *j*, said levers may be turned about their fulcrum-pins into the position indicated 75 by dotted lines at the left of Fig. 2, and the head or cover can be readily removed for filling the barrel or discharging the contents therefrom. When the barrel is filled and the cover is replaced, the levers *j* are turned into 80 the position shown in full lines in the drawings, and the hub *k* is turned about its axis till the inner ends of the levers *j* are firmly clamped, when the barrel will be closed airtight, so that no odors can escape therefrom, 85 thus rendering it practical to transport swill or any other offensive liquids or semi-liquids on the cars. This is a great advantage, especially when the matter is to be transported to a considerable distance, as is often the case 90 with the offal of cities, which is now transported in carts in bulk drawn by horses, often to a distance of five to ten miles, because the railroad companies will not transport it on account of its offensive odor. This objection 95 is entirely obviated by my invention.

What I claim as new, and desire to secure by Letters Patent of the United States, is—

1. In a barrel for transporting odoriferous substances, the combination of a barrel-body 100 having secured thereto a plurality of ears *i i*, a removable head or cover composed of a

wooden disk, and a metal flange-ring secured thereto and projecting beyond the periphery thereof, an annular rubber gasket secured between said wooden disk and the flange-ring, 5 a plurality of cam-levers fulcrumed on said ears and constructed and arranged to press said cover firmly against the ends of the staves, and a locking-cam constructed and arranged to engage with the inner ends of said cam-le-
vers and firmly clamp them in closed positions.

2. The combination, in a barrel, of the staves *a*, a detachable cover composed of the wooden disk *b*, the metal flange-ring *c*, and the central hub *e*, all firmly bolted together, the rubber

gasket *h*, the ears *i i*, firmly secured to said 15 staves, the cam-levers *j j*, pivoted to said ears, the stud *f*, the revoluble locking-hub *k*, pro-
vided with the slots *k' k'*, and the cam-sur-
faces *m m*, substantially as described.

In testimony whereof I have signed my 20 name to this specification, in the presence of two subscribing witnesses, on this 13th day of May, A. D. 1890.

HARVEY C. STROUT.
